CLAIM

The ornamental design for a birdcage attachment, as shown and described.

DESCRIPTION

FIG. 1 is a perspective view of a birdcage attachment;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the design that are shown in broken lines do not form part of the claimed design.
